UNITED STATES PATENT OFFICE

CHARLES E. KRUEGER, OF ST. PAUL, MINNESOTA

VEHICLE RADIATOR CONDENSER

Application filed July 20, 1929. Serial No. 379,825.

This invention relates to condensers and its general object is to provide a condenser primarily designed for vehicle radiators to prevent loss of anti-freeze solution and water 5 therefrom, due to expansion thereof under the action of heat.

A further object of the invention is to provide a condenser for vehicle radiators that will condense the vapors in the cooling system of a motor vehicle and return the condensation to the system in an expeditious manner, whereby loss of liquid from the system will be eliminated.

Another object of the invention is to provide a condenser of the character set forth, that employs the usual radiator cap, is neat in appearance, simple in construction, easy to install, inexpensive to manufacture, and extremely efficient in operation and service.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a front view of my condenser in applied position on the radiator of a motor vehicle.

Figure 2 is a sectional view taken approximately on line 2—2 of Figure 3, with the usual radiator cap applied thereto.

Figure 3 is a top plan view with the cap removed.

Referring to the drawings in detail, the 40 letter A indicates the usual inlet spout of a vehicle radiator, and which is threaded for the purpose of accommodating the usual radiator cap B, but in the present instance, threadedly receives the condenser which 45 forms the subject matter of the present invention.

The condenser includes a housing 1 which as shown is of cylindrical formation, and the housing includes a base portion 2 that is 50 relatively thick as best shown in Figure 2,

and is provided with internally arranged threads for receiving the threads of the inlet spout.

The housing also includes a body portion 3 that is provided with vertically disposed slots 4 arranged therethrough and about the circumferential surface thereof, in a manner whereby the slots are equi-distantly spaced with respect to each other as suggested in Figure 1.

The upper edge of the body portion 3 is exteriorly threaded to accommodate the cap B and passing vertically through the threads are grooves 5 that act as vent openings as will be apparent upon inspection of Figure 2.

Arranged adjacent the top of the body portion and secured therein in any appropriate manner is a disk 6 that fits the inner wall of the body portion and is provided with a plurality of openings which have secured 70 therein and depending therefrom a like number of tubes 7, the tubes being of a length to reach within the radiator as clearly shown in Figure 2.

The base portion of the housing is provided with an annular shoulder that receives therein a disk 8 that is slightly larger than the disk 6 but is likewise provided with openings through which pass the tubes 7. A gasket 9 is arranged in contacting engagement with the disk 8 and is engageable with the top of the inlet spout A so as to form a leak proof joint as will be apparent.

From the above description and disclosure in the drawings, it will be obvious that I 85 have provided a condenser that is primarily designed for vehicle radiators but of course it can be employed with any water cooled engine radiator without departing from the spirit of the invention, and as the water and 90 anti-freeze solution within the radiator vaporizes, the vapors will pass upwardly through the tubes 7, and due to the fact that the tubes are disposed in the path of air entering the slots 4, the adjacent parts of 95 the tubes will be retained in a cool condition with the result the vapors will be condensed whereby the condensation will fall by gravity downwardly through the tubes and thence be returned to the radiator cham- 100

ber, therefore loss of anti-freeze solution and water will be prevented so that a proper amount of cooling liquid will remain in the radiator at all times.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A condenser of the character described comprising, a cylindrical housing, a relatively thick base portion formed therewith and being threaded to accommodate the inlet spout of a radiator, a body portion included in said housing and provided with slots, said body portion being threaded to accommodate a cap, and tubes arranged in said housing in the path of air entering the slots and extending into the radiator.

2. A condenser comprising a cylindrical housing threaded at its lower end to receive the spout of a radiator and threaded at its upper end to receive the cap of the spout, said cylindrical housing being provided with vertically arranged slots formed therein and opening to the atmosphere, tubes supported in said cylindrical housing and extending into the radiator, and said cylindrical housing having grooves arranged vertically therein and being designed to act as vent openings.

3. A condenser comprising a cylindrical housing, a base portion formed therewith and being threaded to receive the inlet spout of a radiator, a body portion included in said housing and being slotted, said body portion being threaded to accommodate the radiator cap, an apertured disk secured adjacent the top of the body portion, an apertured disk arranged in the base portion, said disks being provided with openings, tubes secured to said disks and passing through said openings, said tubes being arranged in the path of air passing through the slots and extending into the radiator, and said body portion being provided with grooves to provide vent openings.

4. A condenser comprising a housing threaded at its lower end to receive the inlet spout of a radiator and at its upper end to receive the radiator cap, said housing being provided with vertically arranged equidistantly disposed slots, a disk provided with openings and arranged adjacent the top of said housing, a disk provided with openings and disposed against a shoulder formed in said housing, a gasket engaging the last mentioned disk and spout to provide a leak proof joint, tubes secured to said disks and being arranged in the path of air passing through the slots, said tubes extending into

the radiator, and said housing being formed with vertically arranged grooves extending through the top thereof to provide vent openings.

In testimony whereof I affix my signature.

CHARLES E. KRUEGER.
